J. J. BOTSFORD

HOSE SUPPORTER

Filed July 11, 1927.

Inventor

Jeannette Botsford

By *Robert G. Smith*

Attorney

Patented June 5, 1928.

UNITED STATES PATENT OFFICE.

JEANNETTE J. BOTSFORD, OF SPOKANE, WASHINGTON.

HOSE SUPPORTER.

Application filed July 11, 1927. Serial No. 204,738.

My present invention relates to improvements in hose supporters which while adapted for use in supporting men's socks are especially designed for supporting women's stockings. In the form of the invention as here exemplified the hose supporter is shown adapted to be attached to the corsets and for connection with the stocking above the knee. The invention involves the use of a pair of interlocking loops that are especially fashioned in such manner that one is placed under the stocking and the other over the stocking so that the material may frictionally be retained by the interlocking parts or gripping jaws of the loops. The grip on the material is spread over a considerable area and the material, as gripped between the jaws of the interlocking loops, is thus relieved of strains, or rather the strains are spread over a considerable area with the result that the stockings are not subjected to tearing action.

The invention consists in certain novel combinations and arrangements of the pair of gripping loops as will hereinafter be more fully pointed out and claimed.

In the accompanying drawings I have illustrated one complete example of the physical embodiment of my invention wherein the parts are combined and arranged according to the best mode I have thus far devised for the practical application of the principles of my invention.

Figure 1 is a view illustrating the utility of the hose supporters.

Figure 2 is an enlarged view showing the suspending web, pair of loops and attaching tape or ribbon, the parts being illustrated in unfastened position.

Figure 3 is a view illustrating the fastening of the stocking between the jaws of the loops.

Figure 4 is a side view of the fastened supporter of Figure 3.

In the drawings I have illustrated the hose supporter adapted for women's wear in connection with the stocking H, and the supporter comprises a folded suspending strap 1 which may be fashioned of suitable material as an elastic web, or inelastic tape, ribbon or other similar desirable material. At its ends the folded suspending strap is provided with casings 2 in which the loops 3 and 4 are supported, said loops being made up of suitable metal and preferably resilient. The suspending strap is loosely supported

in the suspending plate 5 which is slotted at 6 to accommodate the strap and permit it to slide or slip through the slot to compensate for relative movement of the end loops in fastening or unfastening the supporter.

By means of an attaching tape 7, which is provided with an end casing 8, the suspending plate is supported, and the tape 65 may be secured in suitable manner to the corsets C or other suitable garment of the wearer.

In fastening the supporter, the loop 3 is designed to be slipped under the stocking, and this loop as best seen in Figure 2 is provided with an end jaw 9 and restricted portions 10 10 forming a neck between the jaw and the opposite end of the loop.

As best seen in Figure 4 the loops are not flat, but their lower ends, or rather their gripping jaws, are offset from the remainder of the loop to provide for the necessary frictional and interlocking engagement of the loops.

The loop 4 is fashioned with a gripping jaw 11, and a neck portion 12.

In use the loop 3 is slipped under the stocking, then the loop 4 is applied thereto, outside of the stocking by slipping the jaw 11 over the jaw 9 as indicated in Figures 3 and 4. After the loop 3 is placed under the stocking, the loop 4 is turned sideways or edgewise and inserted through the loop 3 pushing the material through said loop, after which the loop 4 is turned within the loop 3 to frictionally engage the material between the two gripping jaws of the loops, and fasten the supporter to the hose. The grip on the stocking is thus distributed over a large surface or area of the material thereby reducing the liability of tearing the stocking due to strains or pulls thereon by the supporter.

A sliding ferrule or band 14 engaging the suspending straps 1 may be slipped back when adjusting the hose supporter and run down to the loops when the adjustment is made to insure that the loops will not be displaced by the movements of the wearer.

Having thus fully described my invention, what I claim as new and desire to secure by Letters Patent is:—

1. A hose supporter comprising a supporting member, a web suspended thereon, a pair of loops on the ends of the web, a slideable ferrule surrounding and frictionally

engaging the web to prevent displacement of the loops and co-acting means on the ends of the loops whereby the hose may be gripped and frictionally retained between the ends of the loops.

2. The combination in a hose supporter with a suspending web and a pair of loops on the web, of an end jaw and a neck portion fashioned on one loop, and an end 10 jaw, a neck portion and outspreading shoul-

ders formed on the other loop, whereby the hose may be gripped and frictionally retained between the ends of the loops, and 15 slideable means on the web ends for clasping the web ends to prevent displacement of the loops.

In testimony whereof I affix my signature.

JEANNETTE J. BOTSFORD.
